UNITED STATES PATENT OFFICE.

OTTO A. HOKANSON, OF WOODSTOCK, ILLINOIS, ASSIGNOR TO WOODSTOCK TYPEWRITER COMPANY, OF WOODSTOCK, ILLINOIS, A CORPORATION OF ILLINOIS.

ESCAPEMENT MECHANISM FOR TYPEWRITERS.

Application filed August 25, 1921. Serial No. 495,331.

To all whom it may concern:

Be it known that I, OTTO A. HOKANSON, a citizen of the United States, residing at Woodstock, in the county of McHenry and State of Illinois, have invented certain new and useful Improvements in Escapement Mechanism for Typewriters, of which the following is a specification.

This invention relates to escapement mechanism for controlling the platen carriage movement on typewriters and is especially applicable to typewriters in which the platen carriage is pivoted to fold relative to the supporting frame.

15 The invention has for its object the provision of mechanism of the class named which shall be of improved construction and operation. It is exemplified in the combination and arrangement of parts shown in the accompanying drawings and described in the following specification, and it is more particularly pointed out in the appended claims.

In the drawings—

25 Fig. 1 is a vertical sectional view of a portion of a typewriter having one embodiment of the present invention applied thereto;

Fig. 2 is a vertical section substantially on line 2—2 of Fig. 1; and

30 Fig. 3 is a horizontal section substantially on line 3—3 of Fig. 2.

The main frame of the typewriter is designated by the numeral 10 and carries a platen carriage frame 11 supported on two arms 12 which are pivoted at 13 on the opposite sides of the main frame 10. A platen carriage 14 is supported by ball bearings 15 which travel in ways 16 on the platen carriage frame. A rack 17 is secured to the platen carriage 14 by lever arms 18 having a finger piece 19 by means of which the rack may be swung into and out of engagement with a pinion 20. The pinion 20 is secured to a stud shaft 21 journaled in the carriage frame 11 and provided at its lower end with an escapement wheel 22. Any usual spring mechanism may be provided for drawing the carriage along its ways 16. The movement of the carriage is controlled by the escapement

50 wheel 22 which is provided with a fixed dog 23 and a pivoted dog 24. The fixed dog 23 is formed integrally with a rocker plate 25 which is supported by pivot pins 26 threaded in ears 27 which extend downwardly from a

bracket 28 carried on the lower face of the 55 platen carriage frame 11.

The movable dog 24 has a pin and slot connection 30 with the rocker plate 25 and a spring 31 normally draws the dog toward the teeth of the escapement wheel 22. A 60 stop 32 is provided for limiting the movement of the dog upon its pivot. A retainer strip 33 is riveted to the lower side of the rocker plate 25 and bears against the lower face of the movable dog 24 to hold it in 65 place on the rocker plate.

The bracket 28 is provided with a downwardly bent tongue 34 forming a stop for limiting the upward movement of the rocker plate. The position of this stop may be adjusted by bending the tongue 34 one way or the other. A spring 35 is seated in a depression 36 in the bracket 21 and presses the rocker plate 25 against the stop 34. An adjustable stop screw 37 limits the movement 75 of the rocker plate in the opposite direction. The plate 25 is actuated by an oscillating member 38 pivoted at 39 on the lower face of the platen carriage frame 11. A finger 40 of the oscillating member 38 extends beneath an offset flange 41 on the tailpiece of the rocker plate 25. A stop screw 42 is threaded in a lug 43 projecting from the oscillating member 38 for limiting the movement of the member in clockwise direction, 80 as viewed in Fig. 2. A link 44 is provided with a goose-neck portion 45 which is pivoted to the oscillating member 38 at 46. The opposite end of the link 44 is pivotally connected at 47 to a bell crank lever 48 pivotally mounted at 49 on a bracket 50 secured to the lower face of the platen carriage frame 11. The bell crank lever 48 is operated by a link 51 extending forwardly substantially parallel to the arm 12 to a point adjacent the 85 pivot 13. The forward end of the link 51 is pivoted at 52 to an arm 53 extending upwardly from a yoke 54 pivotally mounted on a stud 55. A spring clip 56 engages a groove in the periphery of the pivot 52 to hold the link 51 in pivotal engagement with the arm 53.

The yoke 54 adjacent the end of the stud 55 is provided with a downwardly extending arm 57 to the lower end of which is pivotally connected a link 58. The opposite end of the link 58 is pivoted to an upwardly extending arm 59 of a bell crank lever 60

having a rearwardly extending arm 61. A link 62 connects the arm 61 with a universal bar 63 of the typewriter which extends transversely of the machine in position to be engaged by the key levers 64 when they are depressed. An oscillatory bar 65 has each end thereof journaled at 66 in the frame 10 and is provided with a forwardly extending arm 67 having a pin and slot connection 68 with the end of the arm 61. A spring 70 normally draws the arms 61 and 67 upwardly, which motion is transmitted through the link mechanism described to the oscillatory member 38 thus retaining the oscillatory member in its retracted position, as shown in Fig. 2.

Whenever a key lever is depressed the motion imparted to the universal bar 63 will be transmitted through the link mechanism described to the oscillatory member 68 moving the finger 40 upwardly into contact with the flange 41, thus operating the rocker plate 25 to actuate the escapement dogs 23 and 24 and permit the escapement wheel 22 to rotate an amount equal to one tooth thereon. It will be apparent that the parts can be proportioned to time the movement of the escapement wheel properly relative to the movement of the type bars.

When the platen carriage frame is moved about its pivot 13 into folded position the link 51 will swing about its pivot 52 and the operative connection between the universal bar 63 and the escapement mechanism will remain intact independently of the position of the platen carriage frame. It is thus unnecessary to provide any releasable connection between the escapement mechanism on the platen carriage frame and its actuating means on the main frame, the connection being undisturbed by the folding operation of the typewriter.

For letter spacing independently of the type bars the ordinary spacing bar is provided which is attached to a pair of levers 71 carried on a cross-bar 72 pivoted in the side plates of the main frame. The rear end of one of the levers 71 enters a slot in the bar 73 mounted to slide vertically on the face of the rear frame plate. The upper end of the bar 73 is provided with a forwardly projecting flange 74 which extends beneath the tail piece of the rocker plate 25, as shown in Fig. 2. Pressure on the space bar will thus lift the tail of the rocker plate and operate the escapement dogs to permit a letter spacing movement of the platen carriage.

I claim:—

1. In a typewriter, a main frame, a platen carriage frame pivotally mounted thereon, escapement mechanism mounted on said platen carriage frame, key levers mounted on said main frame, and link mechanism for actuating said escapement mechanism from

said key levers, said link mechanism having a pivotal connection therein arranged in approximate alinement with the pivot of said platen carriage frame to permit movement of said platen carriage frame while preserving the continuity of said link mechanism. 70

2. In a compactible typewriter, a main frame, a platen carriage frame pivotally mounted thereon for movement into and out of operating position, escapement mechanism carried by said platen carriage frame, key levers on said main frame, a non-separating folding operative connection between said key levers and said escapement mechanism for operating said escapement mechanism, and letter spacing means for operating said escapement mechanism independently of said connection between said key levers and said escapement mechanism. 75 80

3. In a compactible typewriter, a main frame, a platen carriage frame pivoted on said main frame for movement into and out of operating position, escapement mechanism on said platen carriage frame, key levers on said main frame, foldable connecting means 90 between said key levers and said escapement mechanism arranged to permit folding movement of said platen carriage frame while maintaining the continuity of said connection, and means independent of said connection for operating said escapement mechanism for letter spacing. 95

4. In a compactible typewriter, a main frame, a platen carriage frame pivotally mounted on said main frame for movement into and out of operating position, key levers on said main frame, means for connecting said key levers with said escapement mechanism to actuate said escapement mechanism, said connecting means having a joint 100 105 therein arranged in approximate alinement with the pivotal axis of said platen carriage frame to permit movement of said platen carriage frame while maintaining the continuity of said connection, and means for operating said escapement mechanism for letter spacing independently of said key levers. 110

5. In a folding typewriter, a main frame having a platen carriage frame pivoted 115 thereon for movement into and out of operating position, escapement mechanism on said platen carriage frame, key levers on said main frame, a non-separating pivotally folding connection for actuating said escapement mechanism from said key levers, said connection being arranged to maintain its continuity during folding movement of said platen carriage frame, and letter spacing 120 means for operating said escapement mechanism. 125

6. In a typewriter, a main frame, a platen carriage frame pivoted thereon, escapement mechanism including a dog rocker mounted on said platen carriage frame, key levers on 130

- said main frame, a folding operative connection between said key levers and said platen carriage frame arranged to engage said dog rocker to operate said escapement mechanism, and letter spacing mechanism arranged to engage said dog rocker independently of said foldable connecting means to operate said escapement mechanism for letter spacing.
10. 7. In a typewriter, a main frame having a platen carriage frame pivoted thereon, a lever pivotally mounted on said main frame and having one end thereof positioned adjacent the pivotal axis of said platen carriage frame, escapement mechanism on said platen carriage frame, and means connected with the said end of said lever for operating said escapement mechanism.
15. 8. In a typewriter, a main frame having a platen carriage frame pivoted thereon, a lever pivotally mounted on said main frame and having one end thereof arranged in approximate alinement with the pivotal axis of said platen carriage frame, key levers on said main frame connected with said lever for operating said lever, escapement mecha-
- nism on said platen carriage frame, and a link pivoted to the end of said lever adjacent the pivotal axis of said platen carriage frame for operating said escapement mechanism when a key lever is depressed.
10. 9. A typewriter having a main frame with a platen carriage frame mounted thereon, escapement mechanism on said platen carriage frame comprising a dog rocker, a bell crank lever on said platen carriage frame, means for moving said dog rocker, a link extending along said platen carriage frame transversely of said typewriter and connecting the operating means for said dog rocker with said bell crank lever, a second link connected with the other arm of said bell crank lever and extending forwardly from said platen carriage frame to a position adjacent the pivotal axis of said frame, and means connected with the forward end of said second link for actuating the same to move said dog rocker.
15. In testimony whereof I have signed my name to this specification on this 22nd day of August, A. D. 1921.
20. OTTO A. HOKANSON.
